CLAIM

The ornamental design for a drop down hand rail, as shown and described.

DESCRIPTION

FIG. 1 is a perspective view of a first embodiment of a drop down hand rail, showing our new design;

FIG. 2 is an elevational view from one side of the drop down hand rail, as shown in FIG. 1, the other side matches;

FIG. 3 is a rear view of the drop down hand rail, shown in FIG. 1;

FIG. 4 is a plan view from below of the drop down hand rail;

FIG. 5 is a front view of the drop down hand rail;

FIG. 6 is a plan view from above of the drop down hand rail; and

FIG. 7 is an enlarged perspective view of a two-part clamping knuckle used in the drop down hand rail;

FIG. 8 is a perspective view of one side of one part of the clamping knuckle, shown in FIG. 7, the other part matches; and,

FIG. 9 is a perspective view of the other side of one part of the clamping knuckle, shown in FIG. 7, the other part matches.
